UNITED STATES PATENT OFFICE.

BERNARD F. McALHATTEN, OF NEW YORK, N. Y.

BED FOR SHIPS AND HOSPITALS.

Specification of Letters Patent No. 34,583, dated March 4, 1862.

To all whom it may concern:

Be it known that I, BERNARD F. McALHATTEN, of New York, in the county and State of New York, have invented a new 5 and Improved Bed for Ships and Hospitals; and I do hereby declare that the following is a full and exact description of the same, reference being had to the accompanying drawing and to the letters of reference 10 marked thereon.

Figure I represents a longitudinal section and Fig. II shows a top view of my improved bed.

The nature of my invention consists in the 15 construction of a bed to be used either as a berth on board a ship or as a bed in hospitals, and arranged in such a manner as to form a life preserving raft in case of danger if on board of a ship or capable of being 20 heated or cooled when used in hospitals.

In the accompanying drawings A and B represent the ends of the bed made of airtight compartments, and provided at the same time with lockers *a* and *b*, closed by 25 suitable doors. These ends A and B are connected together near the bottom by tubes or boxes N, forming the bottom laths of the bed, each tube or box being an airtight chamber. The ends A and B are further 30 connected together on each side by braces *n* and *m* between which a light net-work, *x*, is fastened.

When used as berth on board of ships the same are fitted to a suitable frame work in 35 the cabins, two or three above each other, and arranged to be easily removed in case of danger, when they are lowered into the water and form then life preserving rafts, capable of containing, each, from four to 40 six persons. In this case the ends A and B and the tubes N are made to form air chambers independent of each other, by which arrangement any accident or damage happening to either part will not destroy the effi- 45 ciency of the remaining parts. I prefer to

attach the tubes or boxes N, as well as the side braces *n* and *m*, permanently to the end pieces A and B, so as to make the berth complete, to be used as a raft at a moment's notice, which on account of its lightness can 50 easily be done, but the same may be made in separate parts and arranged to be readily fastened firmly together when wanted to form a life preserving raft by having the tubes or boxes N, as well as the side braces 55 *n* and *m*, ship or unship and capable of being securely fastened when wanted, in which case each separate part can be used as a life preserver.

Provisions may be made to propel each 60 raft by oars, or two, three or more rafts may be attached together and taken in tow by a boat. Water, provisions or other necessary articles can be secured in the lockers *a* and *b*.

When the bed is to be used in hospital the air chambers forming the ends as well as the air chambers forming the bottom laths of the bed are arranged so as to be made to communicate with each other, and are then 70 connected with a steam or hot water pipe, for the purpose of heating either the whole bed or any part of the same by steam or hot water, or ice may be placed into the locker in either of the ends, and the other 75 end and bottom be heated, as the case may require.

What I claim as my invention and desire to secure by Letters Patent is—

The construction of a bed with both the 80 end pieces, and the bottom pieces forming the bottom laths, made of airtight chambers, the whole being arranged and combined in the manner and for the purpose substantially as described and specified.

BERNARD F. McALHATTEN.
